RAILWAY FREIGHT CAR BODY

Franklin P. Adler, Michigan City, Ind., assignor to
Pullman Incorporated, a corporation of Delaware

Filed Sept. 5, 1961, Ser. No. 66,721

Term of patent 14 years

(Cl. D66—1)

Fig. 1.

Fig. 2.

FIG. 1 is a perspective view of a railway freight car body showing my new design.

FIG. 2 is an end elevational view of the car body shown in FIG. 1.

The side and end of the car body not shown in the drawing are substantially the same as those shown.

My design for a railway freight car body is characterized by the rectangular side panel on each side thereof framed by a colored perimetric border, said side panel being contrastingly colored and consisting of three doors and two vertical divider posts.

I claim:

The ornamental design for a railway freight car body, substantially as shown and described.
